WILLIAM F. HELMOND, OF HARTFORD, CONNECTICUT, ASSIGNEE TO UNDERWOOD
TYPEWRITER COMPANY, OF NEW YORK, N. Y., A CORPORATION OF DELAWARE.

TYPE-WRITING MACHINE.

1,214,159.

Specification of Letters Patent. Patented Jan. 30, 1917.

Application filed September 20, 1915. Serial No. 51,520.

To all whom it may concern:

Be it known that I, WILLIAM F. HELMOND, a citizen of the United States, residing in Hartford, in the county of Hartford and State of Connecticut, have invented certain new and useful Improvements in Type-Writing Machines, of which the following is a specification.

This invention relates principally to type-writing machines for writing upon a number of superposed webs or continuous sheets, especially those which are intended to be torn off in sections from the body of the web, as, for example, when the webs comprise a series of printed forms, each adapted to be removed when the typewriting thereon is completed. In such work it is desirable to employ ink ribbons or carbon sheets interleaved with the webs for making the duplicate copies. A machine of this general character is shown and described in the patent to Wernery and Smith, No. 1,132,055, dated March 16, 1915. In that machine, after a section of web, to compose a printed sheet, has been written, the platen is shifted away from the usual feed rollers to release the web and the interleaved carbon sheets; whereupon, by means of a carbon sheet holder, the carbon sheets are drawn back along the web into position thereon for the printing of the next web section; the web itself being drawn forward a measured distance for removal of the printed section thereof, and the next imprinted section thereof being positioned, with the carbon sheets therein, for the printing operation. The same carbon sheets are thus used over and over in the same web form. The carbon-sheet-holder of machines of this nature is usually supported on a carriage which rides on a track on a table attached to the platen carriage. The table, therefore, has letter-feed and reverse movement with the platen carriage; and the carbon-sheet-holder has line-space and reverse movement on the table, toward and away from the platen.

The track for the carbon-sheet carriage should be so laid that binding of the carriage on the track cannot occur, otherwise the machine may be rendered inoperative, or the carbon sheets may be torn. On the other hand, the carbon-sheet carriage should not have undue lateral play on its track if regard is to be had for proper feed of the

paper and regularity of placement of letters in the written line. If the track is made integral with the table, the table, or a part thereof, should be of material which can be machined to make the track true. If the track is not integral with the table, and can be made true before being attached to the table, then it should be of such design, and be so attachable to the table, that its guiding edges can be truly placed with little inconvenience.

An object of the invention is to provide for any irregularity or distortion in the guiding edges of the rails (such as might otherwise cause the carriage to bind thereon), by making one rail do the guiding and control the tendencies of the carriage to lateral play, while the other rail co-operates therewith as a bearing for the carriage, and also, if desired, as a means for holding the carriage to the track. In other words, the carriage may have a certain lateral play on one of the rails, resulting from irregularities or distortion of the guiding edge of the other rail.

In a preferred embodiment of the invention, the table is conveniently and cheaply made of tubing or the like, bent or put together in the form of a rectangular skeleton frame. The tracks are flat strips of metal set on the skeleton frame in tested positions, and then screwed or otherwise fixed thereto. The carriage comprises two trucks, one at each side thereof. One truck carries grooved rollers engaging both sides of one rail of the track and closely set to the rail, so that lateral play of the carriage on that rail is inappreciable. The other truck also carries a grooved roller and a depending guard, between which the corresponding track rail is held; but these last are not set so closely to the rail as to prevent such slight lateral play of the carriage on that rail, as may be due to irregularities or distortion in the guiding edges of the other rail.

Other features and advantages will appear hereinafter.

In the accompanying drawings, Figure 1 is a perspective view of the invention applied to an Underwood typewriting machine, the parts being in position to permit writing upon a work-piece. Fig. 2 is a view in cross-section through the table and carbon-sheet carrier. Fig. 3 is a perspective

view of the truck on which the left-hand side of the carrier is supported; a section of the rail on which it rides being shown with the rollers of the truck in engagement therewith. Fig. 4 is a similar view of the right-hand truck and rail. Fig. 5 is a sectional elevation showing the platen and pressure rolls for feeding the work around the platen.

Reference is made to Fig. 1 for a brief description of the parts which may be common to the present machine and to those of the machine of the above-mentioned Wernery and Smith patent. The platen 10 is fixed on its shaft 11 which is journaled in plates or arms 14 and 15 of a frame fast to a rock shaft 12. The shaft 12 has bearings in the end plates 18 of the usual platen frame. The swinging frame is normally held in Fig. 1 position, for writing, with the platen down against feed rolls. It is swung from this position to its web-releasing position by means of a handle 16, also fast to the rock shaft 12. For locking the swinging frame in Fig. 1 position, the handle 16 carries a pin 17, adapted to be engaged by the hook 18, pivotally mounted on the frame piece 13. A spring 19 yieldingly holds the hook in operative position. In returning the parts to printing position, the pin 17 cams back the hook, so that the locking may be automatic.

A tooth 20 on the hook, in conjunction with a pin 22 on the frame piece 13, determines the return throw and normal position of the swinging frame.

To effect the line-space feed or rotation of the platen, there are provided the usual hand wheel 24 and ratchet wheel 25, both fast to a short shaft 26, mounted to rotate in the left-hand end piece 13 of the platen carriage. In printing position, the shaft 26 is concentric with the platen shaft 11. As is common in Underwood typewriting machines, the ratchet is actuated by a pawl 27 on the usual slide engaged by one arm of a line-space lever 29 pivoted to the carriage frame. A spring returns the slide and pawl to normal position after each operation thereof. A spring detent 34 engages the ratchet wheel to hold the platen against rotary displacement. The driving connection between the shaft 26, whose axis is not changeable, and the platen shaft 11, which swings from one position to another, consists of gears 35, 36 and 37. The gear 35 is fast to the shaft 26; the gear 36 is fast to the platen shaft, and is of the same size and has the same number of teeth as gear 35; and the gear 37 is loose on the axle 12 around which the platen frame swings, and has a face of sufficient width to mesh with both gears 35 and 36. The driving connection between the shaft 26 and platen is thus maintained in all positions of the platen.

In Patent No. 1,182,055, to Wernery and Smith, above referred to, it is shown that

in the operation of removing a printed length from the web, and in re-adjusting the web for printing the next length, the platen is swung from printing position to a position away from the feed rolls; so that the web no longer wraps around the platen, but may be moved freely in substantially a straight line from back to front of the machine. When the platen is in this position, the carbon sheets between the plies or folds of the section of the web to be removed, are drawn back into the length or section of web next to be printed; and, after removal of a length of the web, and re-positioning of the web, the platen is returned to its normal position against the feed rolls.

The web is preferably in a single piece, fan-folded longitudinally, to provide for several copies when carbon sheets are interleaved with the folds. It may also be in a crosswise fan-folded condition before being fed into the machine to permit of compactness and convenience in handling, or it may be fed from a roll. It is fed into the machine over the rear end of a table 38, which, in the present invention, comprises a piece of tubing, bent to form a rectangular frame, the front reach 39 of which has ears 40 attached thereto, by means of which the table is secured to bracket arms 41 on the platen carriage. The table frame is braced by a tube 49, from which depends a bracket 50 carrying a roller 51, which rides on a rail 52, carried by a framework 53, secured to or forming part of the main frame of the machine, and which supports the table at the rear thereof. The roller permits of easy letter-feed movement of the table with the platen carriage. The web is led across the table, over a tie-rod 42 of the platen carriage, down around the platen, between the latter and the feed rolls, up across the printing line, designated by the type 43, under the cutter 44, and onto the paper shelf 45, between the side guides 46, whence, when measured lengths are to be cut, it may be drawn to the gage 54, carried by the bar 54, on the paper shelf. The cutter is shown as a blade secured to a sleeve 47 on the shaft 12, to which sleeve is also secured a finger lever 48 for rocking the cutter into engagement with the web when the latter is to be cut.

The carbon sheets are fed forward with the web by the pressure of the feed rollers on the platen, and, as stated, when a length of web is written and the web released, before the web is cut, the carbon sheets are drawn back along the web from the written, to the next unwritten, length thereof. To provide for these movements of the carbon sheets, the same, in machines of this character, are attached at their rear edges to a traveling holder or carriage. This carriage comprises a plate 55 having a stepped block

56 at each side thereof. Fingers or clips 57, to each of which one carbon sheet may be attached, are secured by screws 58 to the steps 59 of the blocks 56. These fingers are less in length than the width of the web, and are staggered; alternate fingers being secured to the same side of the carriage, so that the fingers may lie in the oppositely directed fan-folds of the web. The steps 59 space the several folds of the web apart, so that the carbon sheets may be moved back along the web without binding or tearing of the sheets or of the web. The carriage plate 55 is mounted on trucks adapted to ride on rails at the sides of the table; and a feature of the present invention relates to the construction of these trucks.

The right-hand truck (see Fig. 3) consists of a plate 60 having at each corner thereof an ear 61, in which is mounted a roller 62. These rollers lie horizontally, and are grooved at 63 to engage, two on each side, a rail 64, supported on the left-hand reach 65 of the tubular skeleton of the table. The right-hand truck consists of a plate 67 having, at each of the right-hand corners thereof, an ear 68, in which is mounted a roller 69, similar to the rollers 62, for engagement with a rail 70 on the reach 71 of the table frame. At the other corners of the truck plate 67 are ears or guard lugs 72 which extend down past the inside edge of the rail 70. The carriage plate 55 is attached to the two truck frames by screws 73.

35 The table skeleton is shown as made of tubing, because it can be cheaply and easily so made; and it may be of a single piece, the ends of which are joined at a corner, or other part of the table, or it may be made in several pieces. Since, however, the carbon-sheet-carrier does not ride directly upon the table frame-members, no particular exactness or regularity of shape of line is required for the latter; and hence the frame may not only be made of tubing, but of pieces of any other suitable material and form. In the present construction provision is made for free movement of the sheet-carrier without undue lateral play of the same, but such provision concerns the rails, and the manner in which the trucks are mounted on the same, rather than the table frame proper, as heretofore.

The rails, 64 and 70, which are shown as two flat metal strips, may easily be made with their edges practically straight. The alignment of the rails on their supporting frame is also easy. The left-hand rail may for instance be placed on the table, then set to true position thereon, and finally fastened to the table, as by means of screws 64^a, with its edges in planes perpendicular to the line of letter-feed movement of the carriage. This rail, it will be noted, is held closely enough by the rollers 62 to prevent lateral

play of the truck thereon, while nevertheless permitting free movement of the truck along the rail. After one rail is in place, the other rail may be temporarily or loosely positioned, and the carrier moved back and forth on the rails, until the true position of the right-hand rail is determined; and that rail may then be secured by screws 70^a. It will be noted (see Fig. 2) that, whereas the rollers 62 snugly embrace the rail 64, there is more or less play provided for the rail 70 between the rollers 69 on the one side and the guards 72 on the other side. This play is to allow for any irregularity or distortion of the rail 64, or of the rail 70, so that the carrier cannot become bound between the two rails. This rail 64 may therefore be considered the rail which actually controls tendencies to lateral play of the carriage. The rail 70 is so positioned, however, that the flanges formed by the grooves 63 in the rollers do not permit the carrier to jump the rail, and this rail therefore cooperates with rail 64 to hold the carrier to the track. A handle 75, attached to the carrier-plate 55, serves as a means for moving back the carrier with the carbon sheets when the web is released.

Variations may be resorted to within the scope of the invention, and portions of the improvements may be used without others.

Having thus described my invention, I claim:

1. In a typewriting machine, a platen, a carriage for holding transfer material between the plies of a work-piece during line-space feed of the transfer material and work-piece, and for shifting the transfer material at intervals backward along the work-piece, a rail for guiding and partly supporting the carriage, grooved guide rolls on the carriage rotatable about vertical axes and embracing opposite sides of said rail to hold the carriage against lateral play on the rail, and a companion supporting rail for said carriage, the latter being provided with a grooved guide roll device to engage said companion rail on one side only.

2. In a typewriting machine, a platen, a carriage for holding transfer material between the plies of a work-piece during line-space feed of the transfer material and work-piece, and for shifting the transfer material at intervals backward along the work-piece, a rail for guiding the carriage, guards on the carriage cooperating with opposite sides of said rail to hold the carriage against lateral play on the rail, a second rail cooperating with the first rail to guide the carriage, and guards on the carriage cooperating with the second rail, said last-named guards arranged to hold the carriage against up and down movement at the second rail and allowing such lateral movement of the carriage on the second rail as may be due to

1. S. 6, 159
- irregularities or distortion in the first rail, whereby binding of the carriage between the two rails is prevented.
3. In a typewriting machine, a platen, a carriage for holding transfer material between the plies of a work-piece during line-space feed of the transfer material and work-piece, and for shifting the transfer material at intervals backward along the work-piece, a rail for guiding the carriage, guards on the carriage coöperating with opposite sides of said rail to hold the carriage against lateral play on the rail, a second rail coöperating with the first rail to guide the carriage, guards on the carriage coöperating with the second rail, said last-named guards allowing such lateral movement of the carriage on the second rail as may be due to irregularities or distortion in the first rail, whereby binding of the carriage between the two rails is prevented, and offsets arranged to prevent said lateral guards from moving up and down at either rail whereby the carriage is prevented from jumping the rails.
4. In a typewriting machine, a platen, a carriage for holding transfer material between the plies of a work-piece during line-space feed of the transfer material and work-piece, and for shifting the transfer material at intervals backward along the work-piece, two rails for guiding the carriage, rollers on the carriage, two on each side of one of said rails, with the rail closely held therebetween and holding the rollers against up and down movement relatively to the rail, and two rollers on one side of the other of said rails, and a guard on the carriage between which and said last two rollers the second rail is held; said second rail operative to hold the rollers thereon against up and down movement, space being provided for such lateral play of the carriage on said second rail as may be due to irregularities and distortion in said first rail.
5. In a typewriting machine, a platen, a carriage for holding transfer material between the plies of a work-piece during line-space feed of the transfer material and work-piece, and for shifting the transfer material at intervals backward along the work-piece, two rails for guiding the carriage, rollers on the carriage, one on each side of one of said rails, with the rail closely held therebetween and holding the rollers against up and down movement relatively to the rail, and one roller on one side of the other of said rails, and a guard on the carriage between which and said last roller the second rail is held; said second rail operative to hold the roller thereon against up and down movement, space being provided for such lateral play of the carriage on said
- second rail as may be due to irregularities and distortion in said first rail.
6. In a typewriting machine, a platen, a carriage for holding transfer material between the plies of a work-piece during line-space feed of the transfer material and work-piece, and for shifting the transfer material at intervals backward along the work-piece, two rails for guiding the carriage, rollers on the carriage, one on each side of one of said rails, with the rail closely held therebetween, and one on one side of the other of said rails, a guard on the carriage between which and said last roller the second rail is held; space being provided for such lateral play of the carriage, on said second rail as may be due to irregularities and distortion in said first rail, and flanges whereby the rollers interlock with the rails to hold the carriage to the rails.
7. In a typewriting machine, a platen, a carriage for holding transfer material between the plies of a work-piece during line-space feed of the transfer material and work-piece, and for shifting the transfer material at intervals backward along the work-piece, two rails for guiding the carriage, rollers on the carriage, one on each side of one of said rails, with the rail closely held therebetween, and one on one side of the other of said rails, and a guard on the carriage between which and said last roller the second rail is held; space being provided for such lateral play of the carriage on said second rail as may be due to irregularities and distortion in said first rail, and said rollers being mounted to rotate on vertical axes and grooved to receive the lateral edges of the rails, so that the carriage is held to the rails.
8. In a typewriting machine, a platen, a carriage for holding transfer material between the plies of a work-piece during line-space feed of the transfer material and work-piece, and for shifting the transfer material at intervals backward along the work-piece, two rails for guiding the carriage, rollers on the carriage, one on each side of one of said rails, with the rail closely held therebetween, and one on one side of the other of said rails, a guard on the carriage between which and said last roller the second rail is held; space being provided for such lateral play of the carriage on said second rail as may be due to irregularities and distortion in said first rail, and a table to which said rails are adjustably attached.
9. In a typewriting machine, a platen, a carriage for holding transfer material between the plies of a work-piece during line-space feed of the transfer material and work-piece, and for shifting the transfer material at intervals backward along the work-piece, said carriage consisting of a plate having means thereon for holding the

- transfer material and trucks to which said plate is attached, one of said trucks being a plate with horizontally disposed rollers thereon, and the other of said trucks being a plate with a horizontally disposed roller and a depending guard, and a track comprising two rails, one of which is closely held between the rollers of one of said trucks, and the other of which is held between the roller and guard of the other truck, space being provided for lateral play of the truck on the last-mentioned rail.
10. In a typewriting machine, a platen, a carriage for holding transfer material between the plies of a work-piece during line-space feed of the transfer material and work-piece, and for shifting the transfer material at intervals backward along the work-piece, and a pair of rails on which the carriage rides, one of said rails alone coöperating with the carriage to control tendencies of the carriage to lateral displacement, and both of said rails holding the carriage against vertical displacement.
15. 11. In a typewriting machine, a platen, a carriage for holding transfer material between the plies of a work-piece during line-space feed of the transfer material and work-piece, and for shifting the transfer material at intervals backward along the work-piece, and a pair of rails on which the carriage rides, one of said rails alone coöperating with the carriage to control tendencies of the carriage to lateral displacement, and the other of said rails coöperating with the first rail to prevent the carriage from moving upward off either rail.
20. 12. In a typewriting machine, a platen, a carriage for holding transfer material between the plies of a work-piece during line-space feed of the transfer material and work-piece, and for shifting the transfer material at intervals backward along the work-piece, a pair of rails on which the carriage rides, one of said rails alone coöperating with the carriage to control tendencies of the carriage to lateral displacement, and both of said rails holding the carriage against vertical displacement, and a table to which said rails are attached in tested positions.
25. 13. In a typewriting machine, the combination with a platen, of a carriage for holding transfer material between the plies of a work-piece during line-space feed of the transfer material and work-piece, and for shifting the transfer material at intervals backward along the work-piece, a table, and rails attached to the table in position thereon for the correct guidance of the carriage, the carriage having a pair of rollers mounted thereon to rotate about vertical axes, said rollers engaging opposite side edges of one of the rails, and thereby controlling the tendencies of the carriage to lateral displacement.
30. 14. In a typewriting machine, the combination with a platen, of a carriage for holding transfer material between the plies of a work-piece during line-space feed of the transfer material and work-piece, and for shifting the transfer material at intervals backward along the work-piece, a table, and rails attached to the table in position thereon for the correct guidance of the carriage, the carriage having a pair of rollers mounted thereon to rotate about vertical axes, said rollers engaging opposite side edges of one of the rails, and thereby controlling the tendencies of the carriage to lateral displacement, the carriage having a pair of rollers mounted thereon to rotate about vertical axes, said rollers engaging opposite side edges of one of the rails, and thereby controlling the tendencies of the carriage to lateral displacement, the carriage also comprising a roller to engage a lateral edge of the other rail, the rollers on both rails being flanged to embrace the rails and hold the carriage against vertical displacement.
35. 15. In a typewriting machine, the combination with a work-holding carriage, of a supporting frame for said carriage, said frame comprising a rod bent to form a rectangle, and rails extending along the sides of the frame and attached thereto, said carriage comprising rollers mounted to rotate about vertical axes and arranged to engage both lateral edges of one of said rails, to thereby control the lateral position of the carriage as it travels lengthwise of the rails, said carriage also having a roller to run on the other rail.
40. 16. In a typewriting machine, the combination with a work-holding carriage, of a supporting frame for said carriage, said frame comprising a rod bent to form a rectangle, and rails extending along the sides of the frame and attached thereto, said carriage comprising rollers mounted to rotate about vertical axes and arranged to engage both lateral edges of one of said rails, to thereby control the lateral position of the carriage as it travels lengthwise of the rails, said carriage comprising a roller rotatable about a vertical axis and engaging a lateral edge of the other rail, the rollers on both rails having flanges arranged to prevent up and down movement of the rollers relative to their rails, whereby the carriage is held against vertical displacement.
45. 17. In a typewriting machine, the combination with a work-holding carriage, of a supporting frame comprising parallel side members, and flat rails extending along and attached to said side members, said carriage comprising trucks having rollers to run on said rails, the rollers on one truck being horizontally disposed and having grooved peripheries to engage both lateral edges of one rail, whereby the carriage is guided and the tendency to lateral displacement controlled by said last-mentioned rail.
50. 18. In a typewriting machine, the combination with a platen carriage, of a frame

connected to the carriage to travel therewith, said frame comprising side rods extending transversely to the direction of travel of the carriage, and parallel flat rails mounted on 5 said side rods and extending lengthwise thereof, and a work-supporting carriage having rollers arranged to run on said rails, one of the rails having its longitudinal edges extending laterally beyond its supporting rod, 10 said rollers comprising a pair arranged to

run on said edges, with the rail therebetween holding the rollers against lateral movement, whereby the lateral position of the carriage as it travels along said rails is controlled by one rail.
